UNITED STATES PATENT OFFICE.

HENRY C. ADAMS, OF ALGONA, IOWA.

HAIR-CRIMPER.

SPECIFICATION forming part of Letters Patent No. 776,636, dated December 6, 1904.

Application filed August 25, 1904. Serial No. 222,126. (No model.)

To all whom it may concern:

Be it known that I, HENRY C. ADAMS, a citizen of the United States, residing at Algona, in the county of Kossuth and State of Iowa, have invented certain new and useful Improvements in Hair Crimpers or Curlers; and I do declare the following to be a full, clear, and exact description of the invention, such as will enable others skilled in the art to which it applies to make and use the same.

My invention relates to improvements in hair crimping or curling devices of that class in which a lock or strand of hair is wound upon a suitable body and retained thereon a sufficient time to give the hair a curly or wavy effect when released from such body.

The object of my invention is to improve and simplify the construction and operation of devices of this character, and thereby render them more efficient and durable in use and less expensive to manufacture.

With this and other objects in view the invention consists of certain novel features of construction, combination, and arrangement of parts, as will be more fully described, and particularly pointed out in the appended claims.

In the accompanying drawings, Figure 1 is a perspective view of my improved hair-crimer, showing the same in its open position. Fig. 2 is a side elevation of the same in its closed position. Fig. 3 is a horizontal sectional view taken on the line 3-3 of Fig. 2. Fig. 4 is a transverse sectional view taken on the line 4-4 of Fig. 2. Fig. 5 is a view similar to Fig. 3 through a slightly modified form of my invention.

Referring to the drawings by numerals, 1 denotes the body portion of a device upon which the hair is wound or wrapped, and 2 denotes a loop or bail for retaining the hair thereon. Said body portion may be constructed of any suitable material and in any desired form; but as shown it comprises a straight strip of wood, celluloid, bone, or other suitable material, preferably rectangular in cross-section, although it may be circular or of any other form. At the outer end of the body portion 1 is formed a notch or recess 3, adapted to receive said bail 2, and upon

the inner end of the body portion is secured by a rivet the other fastening device 4, a cap 5, which is preferably cylindrical in form and provided with an open outer end, in which a cylinder or piston 6 is slidably mounted. At 55 diametrically opposite points in said cap 5 are two longitudinally-disposed slots 7, through which and through said piston 6 a cross-bar 8 projects, as clearly shown in Fig. 4. Instead of the cross-bar 8 passing through the piston 6, as shown, the latter may be formed at diametrically opposite points with two laterally-projecting studs to enter and slide in said slots 7. Said cross-bar is forced to the outer ends of the slots 7 by a coil-spring 9, mounted in said cap 5 between the end of said body portion 1 and the inner end of said piston, the outer end 6^a of which projects beyond the outer end of the cap 5 and forms a push-button or knob by means of which the bail 2 may 70 be moved longitudinally upon the body 1 to engage it with or disengage it from the latter.

The said cross-bar 8 forms a fulcrum for the retaining bail or loop 2, which is preferably constructed of a single piece of spring-wire bent upon itself at its center to form an eye 10 and two curved side portions 11. Said side portions are bent inwardly, as at 12, and have their ends bent to form pivot-eyes 13, through which said cross-bar 8 projects, the 80 ends of said cross-bar being headed, as shown at 14, to retain the eyes 13 upon it. The free or outer end of the loop or bail 2 in rear of said eye 10 is formed with a neck or contracted portion 15, which is held in the notch 85 3 in the body portion 1 by the action of the spring 9 upon the piston 6 and the cross-bar 8, the length of the said loop being such that when said cross-bar is held by said spring in the outer ends of the slots 7 said neck 15 will 90 be seated in said notch 3.

It will be seen that by pushing the end 6^a of the piston 6 into the cap 5 against the tension of its spring the outer or free end of the bail may be readily disengaged from the notched 95 end of the body portion to permit the parts to be swung to the position shown in Fig. 1.

In using the device a lock or strand of hair is wound or wrapped around the central portion of the body 1 when the device is in its 100

open position, and the bail is then swung over the body portion, so that its neck 15 will spring into the notch or recess 3. It will be seen that the side portions 11 of the loop will 5 press the hair upon the body portion and prevent the same from unwinding.

In Fig. 5 of the drawings I have shown the cylindrical cap 5 and the body 1 made of one piece of metal or other suitable material. The 10 inner end of the spring 9 bears against a suitable stop 15, located in the body, as shown. In all other respects the construction and operation of this form of my invention is the same as that of the one previously described.

15 From the foregoing description, taken in connection with the accompanying drawings, the construction and operation of the invention will be readily understood without requiring a more extended explanation.

20 Various changes in the form, proportion, and the minor details of construction may be resorted to without departing from the principle or sacrificing any of the advantages of this invention.

25 Having thus fully described my invention, what I claim as new, and desire to secure by Letters Patent, is—

1. A hair-crimper comprising a body portion having a notch at one end, a bail or loop 30 pivotally connected to the opposite end of the

body portion and also connected thereto for slideable movement longitudinally thereof, the free end of the bail or loop being closed and adapted to engage the notch or recess of the body portion, and a spring to retain said end of the bail or loop in engagement with said notch or recess, substantially as described. 35

2. A hair-crimper having at one end a notch or recess and at its other end a hollow cap formed with longitudinal slots, a cross-bar 40 mounted to slide in the slots in said cap, a loop or bail pivoted upon said cross-bar, and a spring in said cap for forcing said cross-bar outwardly to hold said bail or loop in said notch or recess, substantially as described. 45

3. A hair-crimper having at one end a notch or recess and at its other end a hollow cap having an open end, a projecting piston slidably mounted in said cap, a loop or bail pivotally mounted upon said piston, and a spring 50 in said cap for forcing said piston outwardly to hold said bail or loop in said notch or recess, substantially as described.

In testimony whereof I have hereunto set my hand in presence of two subscribing witnesses. 55

HENRY C. ADAMS.
